C. A. ROBINSON
PILE CUTTING MACHINE

Filed Feb. 7, 1927

UNITED STATES PATENT OFFICE.

CHARLES ANDREW ROBINSON, OF LOWELL, MASSACHUSETTS, ASSIGNOR TO MERRIMACK MAN'G CO., OF LOWELL, MASSACHUSETTS, A CORPORATION OF MASSACHUSETTS.

PILE-CUTTING MACHINE.

Application filed February 7, 1927. Serial No. 166,306.

This invention relates to machines for cutting the pile forming threads of corduroy and similar fabrics. The invention is especially concerned with the mechanism for determining when the cutter guides which normally lie just under the threads which are to be cut have passed above instead of under said threads.

The usual type of cutting machine of this character comprises a series of disk cutters and a guide associated with each cutter, the guides penetrating the weave between the body ply and the pile forming threads. It has been customary heretofore to place a metal strip just above the guides and extending across the entire series of guides, this strip resting upon the surface of the fabric being cut. When any guide is deflected above the threads which are to be cut, it comes in contact with the metal strip and closes an electric circuit which causes the stopping of the machine in a manner well known in this art. If any of the guides should pass downwardly through the fabric they would come in contact with another metal plate or strip over which the fabric is fed and thus close the electric circuit and stop the machine in the same manner.

This arrangement is, in general, sufficiently reliable for cutting ordinary corduroy, but in cutting certain fancy corduroys and other pile fabrics which include more than one set of threads that must be cut, it frequently happens that one or more guides pass above one set of threads while still remaining under another set which should be cut. This latter set of threads prevents the guides from making contact with the metal strip and closing the electric circuit to operate the stop motion.

The present invention deals with the problem presented by these conditions, and it aims to devise a detecting mechanism or contact mechanism which can handle a wider range of work than prior mechanisms. It is a particular object of the invention to devise a contact mechanism for stop motions which can be used satisfactorily in the cutting of fancy corduroys and similar fabrics as well as corduroys of the more common type.

The nature of the invention will be readily understood from the following description when read in connection with the accompanying drawings, and the novel features will be particularly pointed out in the appended claims. In the drawings,

Figure 1 is a perspective view of the more important parts of a pile cutting machine equipped with a detector mechanism embodying this invention;

Fig. 2 is a vertical, cross-sectional view showing, on a larger scale, certain details of the mechanism shown in Fig. 1;

Fig. 3 is a plan view, partly in cross-section, illustrating the manner in which the guides and cutters cooperate; and

Fig. 4 is a cross-sectional view, partly in elevation, showing a detail of the mounting of one of the contact disks.

The mechanism shown in the drawings comprises a series of disk cutters 2 of the usual type, all mounted on a shaft 3. Associated with each cutter is a guide 4 of the type commonly used in machines of this character. The fabric F is fed to the cutters in the direction indicated by the arrow in Fig. 1, travels over the usual metal plate 5, and meets the cutters 2 immediately opposite the rounded upper edge of a guide 6. During the cutting operation the guides 4 are given a short horizontal reciprocating movement which facilitates the entrance of the rounded forward ends of the guides under the loose pile forming threads at the upper side of the fabric, the proper position of the guides being between these threads and the closely woven body ply of the goods.

The plate 5 is connected through a contact post 7 and a conductor 8 to the stop motion (not shown) while the metal guides 4 are also connected through another conductor 9 to the stop motion. Consequently, if the guides 4 should be deflected downwardly through the fabric into contact with the plate 5, they would immediately close the electric circuit and operate the stop motion, thus shutting down the machine.

The mechanism so far described is substantially like that heretofore used.

The mechanism shown as embodying this invention includes a series of contact disks

10 all mounted loosely on a stationary shaft 12 so that they can rotate on and also move up and down on said shaft, this shaft being supported in a series of brackets, one of 5 which is shown at 14. Each of these brackets is secured to or formed integral with a metal strip 15, and this entire series of metal strips is secured to another metal strip or plate 16 which lies immediately above but 10 is separable sufficiently from the plate 5 to permit the web of fabric F on which the plate 16 rests to pass between the two plates 5 and 16. The plate 16 can also move backward and forward on top of the cloth. It 15 will be observed that the disks 10 are supported in yielding contact with the fabric F, and they preferably are so spaced or are of such dimensions that one disk is positioned immediately above each guide 4, the 20 edge of each disk being held out of contact with its respective guide solely by the pile forming threads of the fabric. In practice, however, this alignment of the disks and guides is obtained rather infrequently 25 but the arrangement is such that some disk will contact with any exposed guide. It should be noted that the two metal plates 5 and 16 are electrically connected together. Consequently, if any guide 4 should be deflected upwardly through the fabric, it 30 would engage one of the disks 10 and thus complete the electric circuit necessary to operate the stop motion.

While a smooth-edged circular disk would 35 be more effective than the flat metal strip which has been commonly used heretofore, because the edge of the disk would sink in slightly between the loose threads of filling and make an electrical contact with the 40 cutter guide where a flat metal strip would be held out of contact with the guide by a very few threads, still these disks can be made even more effective by notching their peripheral portions. Preferably the disks 45 are made of a toothed form similar to a cog wheel, as clearly shown in the drawings. With this construction, if a guide is deflected upwardly so that it rises above one set of pile forming threads but still lies under 50 another set, the teeth of the contact disk above it will project between the threads and make a contact with the guide sufficient to close the electrical circuit, so that the 55 machine will be stopped before incorrect cutting has occurred.

The mechanism thus operates very reliably to complete the electric circuit necessary to operate the stop motion whenever any of the guides are deflected upwardly 60 out of their normal positions. At the same time if the guides are deflected downwardly they operate exactly as before to effect the stopping of the machine. While this mechanism is particularly valuable in cutting

fancy corduroys which could not be cut satisfactorily with prior machines for the reasons above explained, it is equally efficient in cutting corduroys of the more common weaves.

A suction hood is shown in the drawings 70 at 18 to remove any portions of threads which are completely severed as is sometimes done in cutting fancy corduroy.

While I have herein shown and described the best embodiment of my invention that 75 I have so far devised, it will be understood that the invention may be embodied in other forms without departing from the spirit or scope thereof.

Having thus described my invention, what 80 I desire to claim as new is:

1. In a machine for cutting the threads of fabrics to form a pile thereon, the combination with a cutter and a guide therefor adapted to enter the fabric between the body portion thereof and the pile forming threads, of a toothed contact disk, and means 85 for supporting said disk in cooperative relationship to said guide.

2. In a machine for cutting the threads of fabrics to form a pile thereon, the combination with a cutter and a guide therefor adapted to enter the fabric between the body portion thereof and the pile forming threads, of a toothed contact disk, and means 95 for supporting said disk with its edge in contact with the fabric immediately above said guide and in position to engage the guide whenever the guide is deflected upwardly out of its normal position.

3. In a machine for cutting the threads of fabrics to produce a pile thereon, a contact mechanism for an electric stop motion comprising the combination of a cutter guide adapted to enter the fabric between the body portion thereof and the pile forming threads, a toothed contact disk, and means 105 for supporting said disk in contact with the fabric immediately above the guide and for rotation by said contact with the cloth.

4. In a machine for cutting the threads of fabrics to produce a pile thereon, the combination of a series of cutters, guides associated with said cutters and each adapted to enter the fabric between the body ply thereof and the pile forming threads, a metal plate underlying said guides and across which the fabric is fed toward said cutters, a series 115 of toothed contact disks, means for supporting said disks with their edges in contact with the fabric immediately above the guides, and circuit connections to said plate, guides and disks.

5. In a machine for cutting the threads of fabrics to produce a pile thereon, the combination of a series of cutters, a guide associated with each cutter, each of said guides being adapted to enter the fabric between 120

the body ply thereof and the pile forming threads, a series of contact disks, a metal plate underlying said guides and across which the fabric is fed toward said cutters, and means for holding said disks with their edges resting on the fabric immediately above said guides and in position to engage

any guide which is deflected upwardly through the fabric, said holding means permitting a limited movement of the disks independently of each other toward or from the surface of the fabric.

CHARLES ANDREW ROBINSON.
